ATTORNEY

UNITED STATES PATENT OFFICE.

CHARLES SOLOMON, OF NEW YORK, N. Y., ASSIGNOR OF ONE-THIRD TO FRANK SOLOMON AND ONE-THIRD TO SOL. DAVIDOVITZ, BOTH OF NEW YORK, N. Y.

ADJUSTABLE CAP.

1,419,771.

Specification of Letters Patent. Patented June 13, 1922.

Application filed May 28, 1921. Serial No. 473,422.

To all whom it may concern:

Be it known that I, CHARLES SOLOMON, a citizen of the United States, and resident of the borough of the Bronx, county of Bronx, city and State of New York, have invented certain new and useful Improvements in Adjustable Caps, of which the following is a specification.

This invention relates to adjustable caps 10 of cloth or other similar material and has for its primary object to provide simple and inconspicuous means whereby the size of the cap may be readily adjusted as may be required to thereby obviate the necessity of the 15 retailer, in order to meet the demands of the trade, to carry caps of each style or pattern in numerous sizes, whereby all possible requirements may be adequately filled.

More particularly, the present invention 20 comprehends the provision of adjustment means for caps which will enable the cap to be accurately fitted upon heads of irregular or abnormal shape. To this end I propose to apply independently adjustable means to 25 the front portion of the cap at each side of the visor. Thus one of these adjustable means might be arranged to provide for an enlargement or expansion of the cap band on one side, while the other of said means 30 is adjusted to contract the opposite side of the cap band. In this manner, it will be apparent that the band or marginal edge portion of the crown or body of the cap may be caused to fit snugly yet comfortably, against 35 the head of the wearer regardless of physical peculiarities or abnormalities.

It is also a further general object of my invention to simplify and improve the construction of such adjustable caps, eliminating 40 the use of unsightly buckles or other strap connecting devices and, on the other hand, to provide such a construction and arrangement of the adjustment means that when the front portion of the crown of the 45 cap is connected to the visor by means of the usual snap fastener, said adjustment means will be practically wholly concealed from view.

In accordance with one construction of the 50 present invention whereby the above enumerated advantages are secured, the marginal band of the cap crown is provided at its ends with free extensions located at opposite sides of the cap visor, each of said extensions carrying a female fastening element and a se-

ries of spaced male fastening elements secured to the underside of the front portion of the cap crown at each side of the central longitudinal line of the visor and with which the fastening element on one of said extensions is adapted to be adjustably engaged. When the band extensions have been adjusted and the front portion of the cap crown is fastened to the visor said band extensions underlie the depressed front portion 65 of the cap crown so that the adjustment means is practically invisible and the cap presents a neat and attractive appearance.

With the above and other objects in view the invention consists in the improved form, 70 construction and relative arrangement of the several parts as will be hereinafter more fully described, illustrated in the accompanying drawing and subsequently incorporated in the subjoined claim.

In the drawing wherein I have illustrated one desirable and satisfactory embodiment of the invention and in which similar reference characters designate corresponding parts throughout the several views, 75

Figure 1 is a perspective view of a cap, one of the adjustable band ends being unfastened;

Figure 2 is a front elevation;

Figure 3 is a fragmentary detail horizontal section illustrating the manner in which the marginal edge of the cap crown is contracted, and

Figure 4 is a diagrammatic view showing in an exaggerated manner the adjustment of 90 the cap into different sizes.

Referring in detail to the drawing, 5 designates the crown of the cap which may be formed either from a single piece of material or may be made up of a plurality of 95 sections or segments of suitable size and shape sewed together along their meeting edges. As herein shown, the material of the cap crown 5 is folded or drawn together at its marginal edge and a finishing band 6 is 100 securely stitched to said edge portion of the cap crown. The lines of stitching terminate in spaced relation to the ends of this band and on opposite sides of the crown 5 so that each end of the band 6 has a free or 105 unsecured extension 7. The front portion of the marginal edge of the crown 5 is stitched or otherwise suitably secured to the visor 8 which may also be made of the same material as the cap crown 5, properly rein- 110

forced, or may be constructed of other material so as to present a contrast to the body of the cap. The opposite side edges of the cap visor 8 at their point of attachment to the marginal edge of the cap crown, indicated at 9, are spaced from the termination of the lines of stitching or other securing means whereby the finishing band 6 is attached to the marginal edge of the cap crown. Thus there is provided a short portion 10 of the marginal edge of the cap crown 5 between each side edge of the visor and the end of the attached portion of the band 6 which may buckle or fold upon itself 15 as I have illustrated in an exaggerated way at 10' in Figure 4 of the drawing.

The underside of the front portion of the cap crown 5 is provided with a female fastening element 11 which is adapted to receive the male fastening stud 12 fixed upon the upper side of the visor 8. At each side of the fastening member 11, there is also provided upon the crown 5 adjacent to the point of attachment of its marginal edge to 20 the visor 8 a series of spaced male fastening studs 13. Each end portion 7 of the band 6 is provided at its extremity with a female fastener 14 adapted for engagement with any one of a series of studs 13.

30 In the use of my invention, a cap of maximum size is provided with the extremities of the free end portion 7 of the cap band connected to the outermost stud 13 in each series. When it is desired to decrease the 35 size of the cap, either in fitting the cap upon the head of a purchaser or in order to compensate for stretching of the material after the cap has been worn, the band ends are disconnected from the outermost studs 40 13 and an inward pull exerted thereon as indicated by the arrow in Figure 3 of the drawing so as to engage the fastening elements 14 on the band ends with the intermediate studs 13 or with the inner studs as 45 may be required. Also, in case the head of the wearer is of an irregular or unusual shape the band ends may be connected to differently located studs in the respective series with relation to the central line of 50 the cap and one side of the cap contracted to a greater extent than the other. In this matter a very accurate though comfortable fit can be obtained, which would not be possible if the ends of the band were connected 55 to each other by means of a buckle or other equivalent means as has heretofore been proposed.

From the foregoing description considered in connection with the accompanying drawing, the construction, manner of use and

several advantages of my invention will be clearly understood. The adjusting means for the cap is quite simple and does not materially add to the manufacturing cost of such caps so that the retail cost thereof to a purchaser will not be materially increased. The adjustment can be easily and quickly effected, and when the front of the cap crown is fastened down upon the visor by means of the fastening elements 11 and 12, 70 it will be apparent that the adjustable ends 7 of the marginal band are practically completely covered by the overhanging front portion of the cap crown and thus concealed from view. The adjusting means does not necessitate any change whatever in the location of the fastening elements 11 and 12 or at all interfere with their easy and quick connection or separation.

I have herein disclosed one practical embodiment of the invention which I have found to be very satisfactory and serviceable in use, but it will nevertheless be understood that the device is susceptible of many modifications in the structural form and arrangement of its several parts and I, accordingly, reserve the privilege of adopting all such legitimate changes as may be fairly embodied within the spirit and scope of the invention as claimed.

I claim:

An adjustable cap, comprising a crown having its marginal edge drawn together to approach the size of the head, a visor secured to the front portion of said marginal edge of the crown, a finishing band stitched around the back portion and over the outer side of said marginal edge to reinforce and stiffen the same, the stitches of said band terminating at the opposite sides of the cap in spaced relation from the visor to provide free ends on the band and relatively flexible marginal edge portions at opposite sides of the visor, the lower edges of said marginal edge portions being substantially flush with the lower edge of the band, and means for independently and adjustably securing the free ends of the band over the front portion of said marginal edge of the crown, said free ends being adapted to be independently drawn taut for gathering together said flexible edge portions of the crown and for maintaining the back portion of the marginal edge of the crown in a relatively taut and stiffened position.

In testimony that I claim the foregoing as my invention, and I have signed my name hereunder.

CHARLES SOLOMON.
